[57] CLAIM

The ornamental design for a vehicle tool box, as shown and described.

DESCRIPTION

FIG. 1 is a perspective view of the vehicle tool box, showing my new design.

FIG. 2 is an end elevation view, the opposite end being a mirror image thereof;

FIG. 3 is a side elevation view, the opposite side being a mirror image thereof;

FIG. 4 is a bottom plan view;

FIG. 5 is a top plan view;

FIG. 6 is a perspective view of a vehicle tool box showing a second embodiment of my design;

FIG. 7 is a left end elevation view of the vehicle tool box shown in FIG. 6;

FIG. 8 is a right end elevation view of the vehicle tool box shown in FIG. 6;

FIG. 9 is a bottom plan view of the vehicle tool box shown in FIG. 6;

FIG. 10 is a left side elevation view of the vehicle tool box shown in FIG. 6;

FIG. 11 is a top plan view of the vehicle tool box shown in FIG. 6;

FIG. 12 is a right side elevation view of the vehicle tool box shown in FIG. 6.
